(57) **CLAIM**

I claim the ornamental design for an adjustable device supporting apparatus, as shown and described.

DESCRIPTION

FIG. 1 is a Perspective view of an adjustable device supporting apparatus showing my new design;

FIG. 2 is a Right-side view thereof;

FIG. 3 is a Left-side view thereof;

FIG. 4 is a Front view thereof;

FIG. 5 is a Back view thereof;

FIG. 6 is a Top view thereof;

FIG. 7 is a Bottom view thereof; and,

FIG. 8 is a Perspective view of an adjustable device supporting apparatus showing in exploded view.

1 Claim, 5 Drawing Sheets**FIG. 1**

FIG. 2

FIG. 3

FIG. 4

FIG. 5

FIG. 6

FIG. 7

FIG. 8
